UNITED STATES PATENT OFFICE.

THOMAS M. PANTALL, OF PUNXSUTAWNEY, PENNSYLVANIA, ASSIGNOR OF
ONE-HALF TO JOHN ST. CLAIR, OF SAME PLACE.

THILL-TUG.

SPECIFICATION forming part of Letters Patent No. 358,785, dated March 1, 1887.

Application filed July 22, 1886. Serial No. 208,742. (No model.)

To all whom it may concern:

Be it known that I, THOMAS M. PANTALL, a citizen of the United States, residing at Punxsutawney, in the county of Jefferson and State 5 of Pennsylvania, have invented certain new and useful Improvements in Thill-Tugs, of which the following is a specification, reference being had therein to the accompanying drawings.

10 Figure 1 is a perspective view of the device; Fig. 2, plan views of the metal face-plate, showing front and back; Fig. 3, a plan of the central stiffening metal washer; Fig. 4, a horizontal or cross section through the center of the device; Fig. 5, a plan view of the strap forming loop or keeper for end of the strap from back-band, also of one of the screws which secure the parts together; Fig. 6, a detail in plan showing how the ends of the tuck-loop are secured.

15 This device belongs to that class known as "thill-tugs;" and the novelty consists in the construction of the several parts and in their combination, all as will now be more fully set 20 out and explained, reference being had to the accompanying drawings.

In the drawings, A denotes the parts through 25 which the thill passes, and B, attached to the part A, the buckle whereby said part is secured to the harness. The part A consists of the exterior metallic rims, C, one on each side, the washers D, the central metallic washer, E, and the exterior strap, F, which passes entirely around the washers, its extension serving 30 as additional means for securing the tug to the harness. The exterior metal rims, C, are shaped alike, and each is nearly circular at the body, and has ends c' projecting upward and downward, respectively. In these ends 35 are holes c''. Between these rims C and inside the loop of strap F are the washers D, made of leather, rubber, or any suitable material. I have now shown four of these washers, but may use any number, this for the most part 40 depending on the thickness of each washer. These washers are in general of the same shape as the metallic plates C, and have in their ends holes d. In these rims the indentations c' at the upper ends allow the rims to fit up snugly 45 against or about the lower part of the buckle-frame. In the leather or rubber washer it is

not absolutely necessary that there should be any exactness of fit about the buckle-frame, so long as free movement for the buckle is provided for. The central metal washer, E, is of 55 like general shape of the other washers and has holes in its ends. I design to have this washer placed so as to come about in the middle of the other washers—that is, centrally between them—thus having an equal number of 60 leather washers on each side of the metal washer. This metal washer adds strength and firmness to the structure. The holes in the end and the central openings in the external plates and washers, when all in place in the 65 made-up device, match or correspond; but the central openings in the washers are a little smaller than those of the outside metal rims, and are finished smooth and even on the inside. When, now, the several parts are 70 adjusted together as has been above generally indicated, the screws or screw-threaded rods or bolts G are passed through the holes at the top and bottom of the metal rims and washers, and being set home draw the metal rims 75 toward each other, and so firmly bind together all the parts. The inner edge of the metal rims will not touch the thill; but this passes through the one opening now formed by the junction of the several washers, and only 80 touches the inner edges of the washers.

It will be observed that the inner face of each metal rim is flanged at c'. This gives a seat for the embracing-strap F, and thus is afforded a neat external finish; also, the inner 85 face of each of the metal rims on one side of the rounded part is cut away at c''. This affords a seat for the end h of the strap H, which forms the tuck-loop or keeper for the end of the strap from the back-band to rest in. The 90 ends h of this piece H are enlarged a little at h', and extended beyond the inner edges of c'', and thus the strap will not pull out when the metal rims are screwed together, as has already been explained, which process clamps 95 the ends of the strap H upon the edges of the openings through the tug. The ends of the strap H are rounded, so as to make a smooth finish with the inner face of the inner edges of the washers.

Instead of screw-threaded rods to hold the several parts of the tug together, bolts may be

used and their ends clinched or headed; but where screws are used there will be easier access to the several parts.

The inside of the washers, where the thill or shaft passes, is so nicely made as to prevent any wear or damage to the same. This device is strong, neat, and durable.

Having now described my invention, what I consider new, and desire to secure by Letters Patent, is—

1. In a thill-tug, exterior metal rims flanged on their inner faces, and having bolt-holes at their upper and lower ends, combined with leather or equivalent washers and a metal washer, each washer having holes at its upper and lower ends, the several parts held together by screw-threaded rods or headed bolts and with a surrounding strap, which also holds a buckle, whereby said tug can be secured to the harness, substantially as described.

2. A thill-tug composed of exterior metal rims having inner flanged edges and washers between the same, the several parts held together by rods or bolts, as described, combined with a strap surrounding said washers

and resting on the flanges of the said rims, substantially as described.

3. A thill-tug formed of exterior metal rims and metal and leather washers between the same, all held together by rods or bolts, substantially as described.

4. The combination of the exterior metal rims, C, indented at c³ in their upper ends, the leather and metal washers D and E, and the uniting-screws, with the strap F and buckle B, substantially in the manner and for the purposes described.

5. The combination of the rims C, each cut away on the inner face at c⁵, with the strap-loop H, having enlarged end h', the washers between said rims, and the screw-threaded bolts G, substantially as and for the purposes described.

In testimony whereof I affix my signature in presence of two witnesses.

THOMAS M. PANTALL.
